FRANK KUHN AND FRANK E. SHAILOR, OF DETROIT, MICHIGAN, ASSIGNORS TO AMERICAN ELECTRICAL HEATER COMPANY, OF DETROIT, MICHIGAN, A CORPORATION OF MICHIGAN.

CONNECTOR FOR ELECTRICALLY-HEATED INSTRUMENTS.

1,154,413.

Specification of Letters Patent. Patented Sept. 21, 1915.

Application filed July 9, 1914. Serial No. 849,937.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Connectors for Electrically-Heated Instruments, of which the following is a specification, reference being had 10 therein to the accompanying drawings.

The invention relates to connectors designed for use on electrically heated instruments and more particularly for electrically heated tools such as sad irons.

It is the object of the present invention to overcome certain defects in constructions heretofore employed, and particularly to provide a more durable attachment between the connector and the instrument.

In the present state of the art it is usual to provide the instrument with terminal contact members which frictionally engage co-operating contacts in a connector plug. As the contacts are connected in close proximity to the instrument they will become heated and as a result oxidized or corroded so as to impair the electrical connection. This in turn results in arcing and a still further burning of the contacts, with a final 30 result that the connection is destroyed. Prior to the use of detachable connectors with electrically heated instruments such instruments were provided with permanently attached connectors, but these, while avoiding some of the contact difficulties had the objection of requiring expert services whenever renewal of the conductor cord was necessary.

With the present invention we have provided a construction which permits of readily attaching or detaching the conductor from the instrument, and which at the same time effectually guards against arcing or other contact difficulties.

In the drawings, Figure 1 is a section through a portion of an electrically heated iron, showing the connection thereto; Fig. 2 is a perspective view of the housing; Figs. 3 and 4 are perspective views of the complementary portions of the insulator; and Fig. 5 is a perspective view of the casing.

A is an electrically heated instrument, such for instance as a laundry iron; B is the heating unit within the casing C of the

iron; and D are terminals of the heating unit which pass outward through an aperture in the casing C. These terminals D are preferably provided with clamping means, such as E, for the attachment of the flexible conductor F, and as the connection 64 remains permanent arcing is avoided. It is, however necessary to protect the terminals both mechanically and from short circuiting electrically, and for this purpose we have provided an insulator covering and a 65 metallic casing for inclosing said insulator covering. As shown in Fig. 1, the insulating covering comprises a pair of complementary molded blocks G and H, which are fashioned to embrace the terminals D and 70 the adjacent portion of the flexible conductor F. The block G is preferably formed with recesses I and I' for receiving the terminals D and connecting channels J and J' for the passage of the two strands of 75 the flexible connector. There is also a cross channel K for receiving a rib or bead L upon the member H and constituting a clamp for the flexible conductor, which relieves the terminal connection from mechanical stress. 80 The two members G and H when placed together in engagement with the terminals D are secured by a metallic housing M preferably telescopically engaged therewith. This housing is also preferably secured to 85 the handle N of the iron which is mechanically secured to the casing C and therefore securely holds the members M, G and H from displacement. The member M is preferably further provided with the nipple O 90 for securing a resilient helix P, the latter forming a guard and protector for the flexible conductor as it passes from the casing.

The parts being constructed as described, they may be readily assembled, and at any 95 time quickly detached, while in assembled position the terminals are thoroughly insulated and are maintained in full connection with the conductor. If at any time it is necessary to renew the connector cord the 100 handle and housing M may be withdrawn, which permits the blocks G and H to be disengaged, exposing the terminals D and the clamps E thereof by which the conductor is attached. This will permit the operator 105 to readily detach and replace the cord, after which the parts may be quickly re-assembled.

What we claim as our invention is:—

1. In an electrically heated instrument, the combination with a heating unit having a projecting terminal, of a casing for inclosing said unit apertured for the passage of said terminal, a flexible conductor having a clamping engagement with said terminal, a sectional insulator for embracing said terminal and adjacent portion of said flexible conductor, a handle detachably engaging said casing, and a housing for said sectional insulator secured to said handle.
2. In an electrically heated instrument, the combination with a heating unit having a terminal projecting therefrom, of a casing inclosing said unit and apertured for the passage of said terminal, a flexible conductor having a clamping engagement with said terminal, a sectional insulator for embracing said terminal and clamping said flexible conductor, and a housing for telescopically engaging said sectional insulator to inclose the same and to maintain a clamping engagement thereto.
3. In an electrically heated instrument, the combination with a heating unit having a terminal projecting therefrom, of a casing for inclosing said unit apertured for the passage of said terminal, a flexible conductor having a clamping engagement with said terminal, insulator blocks for embracing said terminal and clamping the adjacent portion of said flexible conductor, a handle detachably engaging said casing, and a hous-

ing mounted on said handle and telescopically engageable with said insulator blocks to inclose and protect the same.

4. In an electrically heated instrument, the combination with a heating unit having a projecting terminal, of a casing apertured for the passage of said terminal, a flexible conductor having a clamping engagement with said terminal, insulator blocks for embracing said terminal and clamping said conductor, a handle detachably engaging said casing, a housing for said insulator blocks telescopically engageable therewith, and a flexible resilient guard for said flexible conductor secured to and projecting from said housing.

5. In an electrically heated instrument, the combination with a heating unit having a projecting terminal, of a casing for said unit, a flexible conductor having a clamping engagement with said terminal, a channeled insulator block for protecting said terminal and adjacent portion of the flexible conductor, a metallic housing for inclosing said insulator, and a detachable handle for said case upon which said housing is mounted.

In testimony whereof we affix our signatures, in presence of two witnesses.

FRANK KUHN.
FRANK E. SHAILOR.
